UNITED STATES PATENT OFFICE

ARTHUR W. CONLEY, OF CLEVELAND HEIGHTS, OHIO, ASSIGNOR, BY MESNE ASSIGNMENTS, TO THE COROZONE COMPANY, OF WILMINGTON, DELAWARE, A CORPORATION OF DELAWARE

OZONIZER

Application filed December 10, 1928. Serial No. 324,870.

My invention relates to ozonizers, and the principal object of my invention is to provide a new and improved device of this type which shall be simple, inexpensive, quiet, and practical, and shall be suitable for purifying, disinfecting, and deodorizing, as in the toilet and sanitary rooms of hotels, office buildings, railway stations, steamships, public halls, and theaters, or generally in offices, theaters, homes, railway cars, and so on. In the drawing accompanying this specification and forming a part of this application I have shown, for purposes of illustration, one form which my invention may assume, and in the drawing.

Figure 1 is a perspective view of the apparatus showing the parts separated,

Figure 2 is a central vertical longitudinal section taken on the line 2—2 of Figure 3, while

Figure 3 is a transverse section taken on the line 3—3 of Figure 2.

The apparatus herein shown includes a rectangular sheet metal box 11 comprising a base 12 provided with projections 13 carrying feet 14 which are formed of felt to provide a cushion support for the apparatus when it is supported by resting upon a supporting body and are apertured at 15 to permit the passage therethrough of screws by which the device may be attached to any desired support in any position either upright or otherwise. The casing 11 also comprises a top 16 spaced from the base 12 and connected thereto by two sides 17 outwardly displaced at 18 to form recesses 19 contoured to tightly receive and maintain tightly compressed the laminated core 20 of a transformer 21. The core 20 of the transformer 21 consists of two side sections 22 connected by three cross legs, a secondary coil leg 23 about which is wound a suitable secondary coil 24, a primary leg 25 about which is wound a suitable primary coil 26, and a leakage leg 27 provided to increase the action of the device.

Encircling the secondary coil 23 are three separate parts, an inner electrode sheet 28 connected by a conductor 29 to one terminal of the transformer secondary 24, an outer

electrode sheet 30 having a free end 31 extending over the primary coil 26 to be grounded at 32 to the leakage leg 27 of the transformer core 20 which is in turn connected by a conductor 33 to the other terminal of the secondary coil 24, the two electrode sheets 28 and 30 thus being connected to the two terminals of the secondary coil 24, and an insulator sheet 34 interposed between the electrode sheets 28 and 30, projecting laterally beyond these sheets 28 and 30, and being of sufficient thickness and width to prevent puncture and arcing across between the electrode sheets 28 and 30 at any voltage at which the device is built to operate.

The electrode sheets 28 and 30 are preferably rough-surfaced, to increase the ozone generating action thereof, and formed of oxidation-resisting material, to reduce to a minimum vaporization of the metal into the air current; I employ herein aluminum wire mesh, and find that very satisfactory from both points of view, it is distinctly rough-surfaced, and there is practically no vaporization whatever.

The transformer windings and the associated parts are insulated from the casing 11 by means of two insulating trays 35 forming in effect a lining for the casing 11. The two ends of the casing 11 are closed by end plates 36 held in position by bolts 37 passing through apertures 38 and 39 formed respectively in the end plates 36 and in flanges 40 on the casing sides 17. The end plates 36 are also provided with apertures 41 to permit entrance of air into the casing 11 and exit from the casing 11 of the air and the ozone, while one of the end plates 36 is provided with a screw-threaded aperture 42 in which is received an insulating bushing 43 through which pass conductors 44 for connecting the primary coil 26 to a suitable source of electrical energy.

It will be understood by those skilled in the art that in operation a relatively low potential alternating current, for example current at 110 volts, is supplied to the transformer primary coil 26, and that as a result there is induced and generated in the transformer secondary coil 24 an alternating current of 100

relatively high potency, say in the neighborhood of eight or ten thousand volts, and that inasmuch as the secondary coil 24 is connected to the two electrode sheets 28 and 30 the 5 generation of this alternating high potential in the secondary coil 24 imposes upon or between the two electrode sheets 28 and 30 a high alternating potential difference too low to cause puncture but high enough to effect 10 from the electrode sheets 28 and 30 a substantially silent discharge effective to produce ozone from and in the surrounding air, also that the disclosed construction of the electrode sheets 28 and 30 facilitates the production 15 of ozone and increases the quantity thereof, and that the composition of the electrode sheets 28 and 30 decreases the amount thereof vaporized by the discharge. In practice I find to an extent wherein the deterioration 20 is entirely negligible and the vaporization of the sheets cannot be noticed either upon examination of the electrode sheets or by any odor in the air or ozone emerging from the device.

25 Under these circumstances it will be obvious to those skilled in the art that I have provided a new and improved ozonizer, and accordingly that I have accomplished at least the principal object of my invention, 30 also that my invention embodies advantages other than those specifically pointed out or suggested herein, also that the particular embodiment of my invention herein shown and described may be variously changed and 35 modified without departing from the spirit of my invention or sacrificing these advantages, accordingly it will be understood that the disclosure herein is illustrative only, and that my invention is not limited thereto.

40 Having thus described my invention what I claim is:

1. An ozonizer comprising: a core having a plurality of spaced transversely extending legs; a transformer comprising a primary 45 coil disposed about one of said transverse legs, and a secondary coil disposed about another of said transverse legs; a flexible electrode sheet wrapped about said transformer secondary coil, flexibly conforming to the 50 contour of said secondary coil and connected to one secondary terminal of said secondary coil, a second flexible electrode sheet wrapped about said secondary coil flexibly conforming to the contour of said secondary coil, connected to another secondary terminal of said secondary coil, and connected to a third leg of said core, and an insulating sheet interposed between said electrode sheets.

2. An ozonizer comprising: a core having 60 a plurality of spaced transversely extending legs; a transformer comprising a primary coil disposed about one of said transverse legs, and a secondary coil disposed about another of said transverse legs; an electrode 65 sheet disposed about said transformer sec-

ondary coil and connected to one secondary terminal of said secondary coil, a second electrode sheet disposed about said secondary coil, connected to another secondary terminal of said secondary coil, and connected to a third leg of said core, and an insulating sheet interposed between said electrode sheets.

3. An ozonizer comprising: a core having a plurality of spaced transversely extending legs; a transformer comprising a primary coil disposed about one of said transverse legs, and a secondary coil disposed about another of said transverse legs; a flexible rough-surfaced electrode sheet wrapped about said transformer secondary coil, flexibly conforming to the contour of said secondary coil and connected to one secondary terminal of said secondary coil, a second flexible rough-surfaced electrode sheet wrapped about said secondary coil flexibly conforming to the contour of said secondary coil, connected to another secondary terminal of said secondary coil, and connected to a third leg of said core, and an insulating sheet interposed between said electrode sheets.

4. An ozonizer comprising: a core having a plurality of spaced transversely extending legs, a transformer comprising a primary coil disposed about one of said transverse legs, and a secondary coil disposed about another of said transverse legs; a rough-surfaced electrode sheet disposed about said transformer secondary coil and connected to one secondary terminal of said secondary coil, a second rough-surfaced electrode sheet disposed about said secondary coil, connected to another secondary terminal of said secondary coil, and connected to a third leg of said core, and an insulating sheet interposed between said electrode sheets.

5. An ozonizer, comprising a transformer having a core and laterally spaced primary and secondary windings; a first flexible electrode wrapped about said secondary winding and conforming to the contour thereof and supported thereby and connected to one terminal thereof; and a second flexible electrode supported by both of said primary and secondary windings and extending across the space therebetween and connected to another terminal of said secondary winding.

6. An ozonizer, comprising a transformer having a core and laterally spaced primary and secondary windings; said secondary winding having one terminal thereof connected to said core; a first flexible electrode wrapped about said secondary winding and conforming to the contour thereof and supported thereby and connected to the other terminal thereof; and a second flexible electrode connected to said core and extending across the space between said windings and around said secondary winding.

7. An ozonizer, comprising a transformer having a core and laterally spaced primary and secondary windings, said secondary winding having one terminal thereof connected to said core; a first flexible electrode wrapped about said secondary winding and conforming to the contour thereof and supported thereby and connected to the other terminal thereof; and a second flexible electrode supported by both of said primary and secondary windings and extending across the space therebetween and connected to said core.

8. An ozonizer, comprising a transformer having a core and laterally spaced primary and secondary windings; a first electrode of openwork structure wrapped about said secondary winding and conforming to the contour thereof and supported thereby and connected to one terminal thereof; and a second flexible electrode of openwork structure supported by both of said primary and secondary windings and extending across the space therebetween and connected to another terminal of said secondary winding.

9. An ozonizer, comprising a transformer having a core, and laterally spaced primary and secondary windings; a first electrode of woven wire fabric wrapped about said secondary winding and conforming to the contour thereof and supported thereby and connected to one terminal thereof; and a second flexible electrode of woven wire fabric supported by both of said primary and secondary windings and extending across the space therebetween and connected to another terminal of said secondary winding.

In testimony whereof I hereunto affix my signature.

ARTHUR W. CONLEY.
